UNITED STATES PATENT OFFICE.

NISHAN M. BOYAJIAN, OF NEW YORK, N. Y.

DESIGN FOR A HAIR-HOLDER.

SPECIFICATION forming part of Design No. 29,564, dated November 1, 1898.

Application filed September 30, 1898. Serial No. 692,345. Term of patent 14 years.

To all whom it may concern:

Be it known that I, NISHAN M. BOYAJIAN, a subject of the Sultan of Turkey, but having declared my intention to become a citizen 5 of the United States, residing at New York city, in the county of New York and State of New York, have invented and produced a new and original Design for a Hair-Holder; and I do hereby declare the following to be a 10 full, clear, and exact description of the same, reference being had to the accompanying drawings, forming a part thereof.

My invention has relation to a design for hair-holders of new and original shape and 15 configuration, as hereinafter described.

In the accompanying drawings, Figure 1 is a side elevation of the hair-holder. Fig. 2 is a side elevation of the hair-holder.

As shown in the drawings, the leading feature of my design consists in a central portion 1, open in its center and having the outwardly-extending projections 2, as shown, the said projections extending out away from the central portion 1, as shown. 20

Having thus described my invention, what 25 I claim as new, and desire to secure by Letters Patent, is—

The design for a hair-holder herein shown and described.

In testimony whereof I affix my signature 30 in presence of two witnesses.

NISHAN M. BOYAJIAN.
